TUBULAR POSTAL DISPATCHING STATION

Filed Jan. 31, 1929

UNITED STATES PATENT OFFICE

WILHELM HÖHNE, OF BERLIN-CHARLOTTENBURG, GERMANY, ASSIGNOR TO DEUTSCHE TELEPHONWERKE UND KABELINDUSTRIE AKTIENGESELLSCHAFT, OF BERLIN, GERMANY

TUBULAR POSTAL DISPATCHING STATION

Application filed January 31, 1929, Serial No. 336,539, and in Germany February 2, 1927.

In tubular postal systems, particularly those with alternate operation, it was hitherto necessary, to make the container of sufficient weight so that the container inserted 5 into the transmitting tube could slide with certainty through the transmitting tube into the conveying tube, in which it was actuated by the actuating stream of air. On its passage through the transmitting tube the container first meets a resistance due to the friction 10 with the walls of the tube and then also by reason of the fact that at the same time the actuating air from the conveying tube acts in the opposite direction thereto. If the container is too light in weight it may consequently occur, and it has been observed that the container was wedged in the transmission tube or in any case was delayed in transmission. This wedging frequently occurred directly 15 below the transmission flap.

The subject of the present invention is an arrangement by which this wedging of the container is prevented. For this purpose the actuating air from the blower is not only conducted 20 in the usual manner to the conveying tube, in tubular postal systems with alternate operation in the vicinity of the receiving chamber, but also through a valve into the transmitting tube above the container which 25 has been introduced so as to impart movement to the latter by means of the actuating air and thus to force it into the transmitting tube.

The supply of actuating air to the transmitting 30 tube may be effected either by hand or automatically independently upon the opening and closing of the transmitting tube. The simplest form of construction is one in which when the transmission flap is open, the air is cut off from the space above a container which has just been introduced, but when the flap is closed, air is admitted to this space. In order to effect a regular introduction 35 of the container and to effect the transmission thereof by means of the actuating air, the transmission tube, in accordance with the invention, is provided with a transmission chamber into which the container to be dispatched is placed and from which it is forced 40 into the transmitting tube by opening

the supply of actuating air after opening the lower closure of the chamber.

When providing a transmission chamber the inlet of actuating air to the conveying tube is preferably placed directly underneath the lower closure member of the transmission chamber as, if it were placed in a lower position, a counter pressure of the actuating air against the container would again be set up. The transmission chamber formed in this manner is a kind of sluice, which has the advantage, that it permits of the insertion and dispatch of further containers without withdrawing the actuating air from the container already disposed in the tube. In order to relieve the transmission flap from the pressure of the actuating air, the transmission chamber may also be provided with an upper closure which is moved oppositely to the lower closure. The closure members of the transmission chamber (slide or flap) may be actuated automatically by the transmission flap.

In order to effect an automatic change over from suction to pressure, as is usual, in alternate operation, but without causing the transmission flap, which must already, in accordance with the invention, effect the change over of the actuating air, to perform further work, the common pipe extending from the blower, in accordance with the invention, is at one end connected by a branch pipe, provided with a non-return valve, to the transmission pipe or to the change-over valve for the actuating air, and at the other end by a branch pipe, provided with a non-return valve, to the receiving chamber of the station. The non-return valves are so arranged that they only allow actuating air to pass to the transmitting tube and suction air only to the receiving chamber.

One form of construction of the invention is illustrated in the accompanying drawing.

Fig. 1 is a diagrammatic showing of a system which embodies the present invention.

Fig. 2 is a detail view of one of the sending stations.

Fig. 3 is a detail view of the connection between the flap and the valve.

Figure 1 shows two points of a tubular

postal system which are connected together by a conveying tube F and which operate with a reversing drive. At each point the pipe Z, leading from the blower, is connected in the usual manner by a pipe b to the receiving sluice E¹, but at the point of junction of the pipes z and b a nonreturn valve R_s is so arranged that it only allows suction air to enter the pipe b. The receiving sluice E¹ is provided with closing slides s¹, s², actuated by the feelers f¹, f², by the oncoming container, these slides being enclosed in chambers k¹, k².

A pipe a, which is also provided with a non-return valve R_t, leads from the blower pipe Z to a chamber K, and in this chamber the pipe a is connected by means of a reversing valve V and two branch pipes to the transmitting chamber d of the transmitting tube S, as shown to a larger scale in Figure 2.

The transmitting tube S is closed at the top by a transmitting flap S_k movable on a hinge g. The flap actuates, by means of an eccentric h, provided with a slot i, a rod m, longitudinally movable in the bearings n at the side of the transmission chamber d. Levers p with pivoted flaps v¹ and v² are rotatably mounted on the chamber d on pivots o in such a manner that the flaps v¹, v² may be inserted as sliders into corresponding gaps w¹, w² of the transmitting tube. This insertion is effected alternately by the rod m which suitably cooperates with the projections q of the levers p by projections thereon. Figure 2 shows the position of the sliders v¹, v² when the transmission flap S_k is closed. In this position the transmission chamber d is open at the bottom, closed at the top and the valve V is in such a position that the actuating air from the pipe a can enter through the upper branch pipe a¹ into the transmission chamber d above the container (not shown) previously introduced.

The container is then forced out of the chamber d by the actuating air and conveyed into the transmission tube S from which the container passes through the conveying tube F to the receiving point.

The change over of the valve V for this purpose is effected automatically, in a manner shown in Fig. 3, when closing the transmission flap S_k. The pivoted lever r has pin and slot connections with the rod m and the valve V, in such a way that downward movement of the rod raises the valve to close the upper branch tube and vice versa. When opening the flap S_k the valve V is moved into such a position that the actuating air from the pipe a passes into the lower branch pipe a² and consequently under the slider v², which in the meantime has been moved into the gap w² by the downward movement of the rod m. In this position of the transmitter the upper slider v¹ has been withdrawn from the gap w¹ and a fresh container can

now be placed into the chamber d. When closing the flap S_k the lower slider v² is withdrawn, the upper one brought into the closing position and the valve V changed over so that the actuating air from the pipe a now passes through the upper branch pipe a¹ again behind the container and causes this to be dispatched in the manner hereinbefore described.

Instead of the flap S_k any other member (a hand-wheel and the like) may be provided for changing over the valve V and the sliders v¹, v²; in such a case the flap may be entirely omitted.

I claim:

1. In a tubular postal system the combination with a conveying tube of a transmitting chamber located opposite one end of said conveying tube, a closure member for closing the end of said transmitting chamber adjacent the conveying tube, a closure member adapted to close the other end of said transmitting chamber, means for actuating said closure members so that when one is in the open position the other is in the closed position, and means for supplying an actuating fluid to said transmitting chamber and to said conveying tube, and a closed chamber in which the transmitting chamber and the adjacent end of the conveying tube are located.

2. In a tubular postal system the combination with a conveying tube having one end thereof arranged vertically, of a closed chamber receiving the open end of the vertical portion of said conveying tube, a transmitting chamber arranged vertically above the open end of said conveying tube and spaced therefrom, a closure member adapted to engage said space so as to close the open end of said conveying tube and the lower end of said transmitting chamber, a closure member adapted to close the upper end of said transmitting chamber, a feeding funnel leading into the upper end of the closed chamber and terminating above the upper end of the transmitting chamber, a closing flap over said feeding funnel, a fluid supply pipe leading into said closed chamber, two branch pipes leading from the said fluid supply pipe, one of said branches leading to the upper end of said transmitting chamber and the second branch pipe leading to said conveying tube, a valve between said fluid supply pipe and branches and adapted to alternately connect said branches to said fluid supply pipe, and means actuated by said flap for moving one of the closure members into the closed position shortly before it moves the other closure member into the open position.

3. In a tubular postal system the combination with a conveying tube having one end thereof arranged vertically of a closed chamber receiving the open end of the vertical portion of said conveying tube, a transmitting chamber arranged vertically above the

open end of said conveying tube and spaced therefrom, a closure member adapted to engage said space so as to close the open end of said conveying tube and the lower end of said transmitting chamber, a closure member adapted to close the upper end of said transmitting chamber, a feeding funnel leading into the upper end of the closed chamber and terminating above the upper end of the transmitting chamber, a closing flap over said feeding funnel, a fluid supply pipe leading into said closed chamber, two branch pipes leading from the said fluid supply pipe, one of said branches leading to the upper end of said transmitting chamber and the second branch pipe leading to said conveying tube, a valve between said fluid supply pipe and said branches and adapted to alternately connect said branches to said fluid supply pipe, and means actuated by said flap for moving one of the closure members into the closed position shortly before it moves the other closure member into the open position, said means including a plate having an eccentric slot therein and secured to said flap, a vertically sliding rod engaging at its upper end with said eccentric slot, pivotally mounted levers connected to said closure members, projections on said levers, and spaced projections on said rod for cooperation with the projections on the levers.

4. In a tubular postal system, a tube, a fluid supply pipe, branch pipes leading from said fluid supply pipe to spaced points on said tube adjacent one end thereof, a valve between said fluid supply pipe and said branch pipes adapted to connect said branch pipes alternately to said fluid supply pipe, a flap on the end of said tube, and means whereby the opening and closing of said flap actuates said valve.

5. In a tubular postal system, a tube, a pair of gates near one end of said tube, said gates being adapted to open and close alternately, a flap on the end of said tube, and means whereby the movement of said flap actuates said gates.

6. In a tubular postal system, a tube, a pair of gates near one end of said tube, means whereby the opening of one of said gates closes the other of said gates, a flap on the end of said tube, and means whereby the opening of said flap opens one of said gates while the closing of said flap opens the other of said gates.

7. In a tubular postal system, a tube, a pair of gates near one end of said tube, means whereby the opening of one of said gates closes the other of said gates, a flap on the end of said tube, means for supplying air to points in said tube adjacent each of said gates on the sides opposite said flap, means whereby the opening of said flap opens the gate nearest said flap and admits air to said tube at a point adjacent the gate farthest

from said flap, while the closing of said flap opens the gate farthest from said flap and admits air to said tube at a point adjacent to the gate nearest said flap.

8. In a tubular postal system, the combination with a conveying tube of a transmitting chamber located opposite the end of said conveying tube, a feeding funnel in alignment with the end of said transmitting chamber opposite to said tube, a closure member adapted to close said transmitting chamber at one end, a second closure member adapted to close said transmitting chamber at the other end, a flap on said funnel and means whereby the opening of said flap closes said first named closure member and opens said second named closure member, while the closing of said flap opens said first named closure member and closes said second named closure member.

9. In a tubular postal system the combination with a conveying tube of a transmitting chamber located opposite the end of said conveying tube, a feeding funnel in alignment with the end of said transmitting chamber opposite to said tube, a closure member adapted to close said transmitting chamber at one end, a second closure member adapted to close said transmitting chamber at the other end, a fluid supply pipe, a branch pipe leading from said fluid supply pipe to the end of said tube, a second branch pipe leading from said fluid supply pipe to the end of said transmitting chamber adjacent said funnel, a valve between said fluid supply pipe and said branch pipes adapted to connect said branch pipes alternately to said fluid supply pipe, a flap on said funnel, and means whereby the opening of said flap closes said first named closure member and opens said second named closure member and connects said fluid supply pipe with said first named branch pipe, while the closing of said flap opens said first named closure member and closes said second named closure member and connects said fluid supply pipe with said second named branch pipe.

In testimony whereof I have signed my name to this specification.
